UNITED STATES PATENT OFFICE.

ALBERT E. LIBBY, OF HOULTON, MAINE.

DESIGN FOR A GAME-BOARD.

SPECIFICATION forming part of Design No. 31,907, dated November 28, 1899.

Application filed October 28, 1899. Serial No. 735,135. Term of patent 14 years.

To all whom it may concern:

Be it known that I, ALBERT E. LIBBY, a citizen of the United States, residing at Houlton, in the county of Aroostook and State of Maine, have invented and produced a certain new and original Design for a Game-Board; and I do declare the following to be a full, clear, and exact description of the invention, such as will enable others skilled in the art to 5 which it appertains to make and use the same.

The invention relates to a design for a game-board of the configuration shown in the annexed drawing, in which the figure is a perspective view of a game-board illustrating my 10 design.

The leading feature of my design for a game-board consists of the rectangular border formed with three right-angular corners and 15

one round or curved corner. This border has its parallel sides straight and a straight end, 20 while the other end is partly straight and partly curved, as shown.

A continuous rib appears on the face of the board to form a large and a small square communicating with each other. 25

What I claim is—

The design for a game-board, substantially as herein shown and described.

In testimony whereof I have hereunto set my hand in presence of two subscribing witnesses. 30

A. E. LIBBY.
